DROP HAMMER

Arthur T. Murray, Springfield, Mass., assignor to
 Moore Drop Forging Company, Springfield,
 Mass., a corporation of Massachusetts

Original application August 21, 1939, Serial No.
 291,151. Divided and this application July 20,
 1940, Serial No. 346,644

3 Claims. (Cl. 78—25)

This invention relates to drop hammers, and has particular reference to improvements therein in the matter of lengthening the life of the machine parts and facilitating and improving the accuracy of the adjustment of the registration between the hammer and the anvil.

In accordance with the invention the anvil is provided with a pair of vertical guides, each adjustable in two directions at right angles to each other. The hammer operating mechanism is carried in a frame having a massive foundation entirely separate from that of the anvil. By having the guides carried solely by the anvil they function to guide the hammer vertically into exact registration without reference to any strains that may be imposed upon the hammer actuating mechanism. Conversely, the columns supporting the super-structure which carries the hammer operating mechanism are free from all vibrations resulting from the impact of the hammer on the anvil, and the crystallization of the metal in these columns, which has hitherto been a serious cause of fracture, is avoided.

The manner in which these objects are accomplished will be understood best by references to the accompanying drawing, in which:

Fig. 1 is an elevation, partly broken away, of a drop hammer constructed in accordance with my invention; and

Fig. 2 is a side view of the hammer shown in Fig. 1, partly broken away in median section.

This application is a division of my application filed August 21, 1939, Serial No. 291,151.

The hammer 10 may be carried by a strap or board 11 which is operated by suitable mechanism 9 contained in a super-structure 12. The mechanism may be of any desired type, and it is not necessary to illustrate it here. The super-structure is carried upon vertical frames or columns 13 supported in foundations 14 preferably extending a substantial distance below the ground level 15. These foundations are entirely separate from an intermediate foundation 16 which supports the anvil 17. By making the foundations individually massive and separate one from another, transmission of vibration between them will be greatly reduced from that which would occur were the foundations to be formed in one piece. The columns 13 are thus free from the vibrations set up by the shock caused by the hammer striking the anvil. In prior installations, in which the columns 13 arose directly from the anvil, the transmission of vibrations through the column from the anvil to the super-structure and back again by reflection has been a serious cause of strain on the columns, leading to crystallization and final frac-

ture. By having the anvil and the columns each terminating in a separate massive foundation, the free flow of vibrations between them is broken up.

5 In Fig. 2 is shown a detail of the hammer structure which is of considerable value in permitting adjustment of the hammer blow for different types of work and in compensating for the loss of metal occasioned by the necessity of trimming down the hammer after extended use in order to keep its surface in shape. The board 11 is secured to a wrist pin 60 turning freely on a pintle 61 which itself may turn in a bushing 62 in a hole extending laterally through the hammer. 10 A tapered hole 63 is formed vertically in the upper part of the hammer, preferably traversing the bushing 62. Fitting within each vertical hole 63 is the shank 64 of a heavy weight 65. When the weight is in position it forms a stop for the ends of the pintle 61, so that no extra mechanism need be employed to keep the pintle in position. 15 A threaded hole 66 is provided in the hammer below the shanks 64 so that by inserting a threaded rod in each hole 66 the weights may be forced out of wedging contact with the tapered hole. It will be understood that the weights may be replaced as desired for the adjustment of the weight of the hammer either for particular classes of work or to compensate for wear. When once placed in position the weights wedge themselves firmly in place on the first blow of the hammer and cannot work themselves loose.

I claim:

1. In a drop hammer, a hammer having tapered holes having greater diameters at their top than at their bottom, weights having shanks tapered to fit in said holes, and threaded holes aligned with said tapered holes.

35 2. In a drop hammer, a hammer construction comprising a plurality of removable weights having tapered shanks fitting within tapered recesses in the hammer, the hammer and weights being so shaped one relative to the other as to permit a force to be applied between them in a direction to cause loosening of the tapered shank of the weight from its tapered socket, the direction of the taper of the shank and socket being such as to cause the weight to become wedged in place upon the striking of the anvil by the hammer.

45 3. In a drop hammer, a hammer formed with tapered holes of a greater diameter at their upper ends than at their lower ends, and weights having shanks tapered to fit said holes whereby the effective weight of the hammer may be changed 50 by replacing said weights.

ARTHUR T. MURRAY.
